UNITED STATES PATENT OFFICE.

HENRY P. BOYD, OF BELLEVUE, PENNSYLVANIA, ASSIGNOR OF ONE-FOURTH
TO GEORGE A. DICKSON, OF PITTSBURG, PENNSYLVANIA.

ROD CONNECTION.

SPECIFICATION forming part of Letters Patent No. 569,995, dated October 27, 1896.

Application filed May 11, 1895. Serial No. 548,962. (No model.)

To all whom it may concern:

Be it known that I, HENRY P. BOYD, of Bellevue, in the county of Allegheny and State of Pennsylvania, have invented a new and useful Improvement in Rod Connections, of which the following is a full, clear, and exact description, reference being had to the accompanying drawing, forming part of this specification, in which the figure is a side elevation, partly broken away, of a rod connection constructed in accordance with my invention.

My invention relates to the connecting or coupling up of a series of rods for use as stay-rods, oil-well connections, &c., and is designed to provide a connected series of rods which shall consist of but two different types of parts, the rods and correspondingly the sleeves being similar to each other.

In the drawing, 2 represents a coupling-sleeve having at one end a hole 3 of about the same size as the rod, this hole leading into a larger hole or cavity 4, which enlarged cavity receives the heads upon the opposite ends of the two adjacent rods. This larger cavity is screw-threaded for at least a portion of its length, and these screw-threads are engaged by similar screw-threads upon the exterior of a collar 5, which surrounds the rod adjacent to the head. In connecting up the rods, each of which is exactly similar in the connected series, I take a rod having a head at one end, and pushing the other end of this rod through the hole 3 in the coupling-sleeve the sleeve is slid down the rod a sufficient distance to allow the upsetting of this end of the rod into a head 6. The coupling-sleeve is then slid back until this head fits against the shoulder or offset in the sleeve, and the head 7 of the next rod in the

series being pushed into the larger cavity the 40 collar 5, which is slipped over the rod, is screwed into place in the sleeve, thus giving a strong and secure connection for the rods. The sleeve may be provided with a squared portion, if desired, for the application of a 45 wrench to turn the sleeve, and, if desired, a lug 8 may be used upon the sleeve for suspending the series of rods wherever they are used in oil-well connections and similar locations. 50

The advantages of my invention will be apparent to those skilled in the art, since by the use of two simple types of parts, namely, the series of rods, each similar to the other and each having the screw-threaded sleeve, and 55 the series of coupling-sleeves, each similar to the other, a cheap and strong connected series of rods is obtained, thus doing away with the trouble of making and arranging several 60 different types of parts.

I claim—

A series of connected rods, each having at one end an integral enlarged head, an exteriorly-screw-threaded sleeve butting against the head, and engaging the larger innerly- 65 screw-threaded cavity of the coupling-sleeve, and its other end pushed through the smaller hole of the next similar sleeve and then upset so as to form a head of substantially the same size as the head at the other end, substantially as described. 70

In testimony whereof I have hereunto set my hand.

HENRY P. BOYD.
